(57) **CLAIM**

The ornamental design for a backwards clock, as shown and
 described.

DESCRIPTION

FIG. 1 is a front elevational view of the backwards clock of
 the present invention;

FIG. 2 is a rear elevational view of the backwards clock of
 FIG. 1;

FIG. 3 is a left side elevational view of the backwards clock
 of FIG. 1, the right view being a mirror image thereof;
 FIG. 4 is a top plan view of the backwards clock of FIG. 1;
 and,

FIG. 5 is a bottom plan view of the backwards clock of FIG.
 1.

The broken lines showing of hour, minute and second hands
 in FIG. 1 is for illustrative purposes and form no part of the
 claimed design.
